UNITED STATES PATENT OFFICE.

FERNANDO WHITE, OF PITTSBURG, PENNSYLVANIA, ASSIGNOR OF ONE-HALF TO WILLIAM YAGLE & CO., (LIMITED,) OF SAME PLACE.

GAS-BURNER.

SPECIFICATION forming part of Letters Patent No. 399,104, dated March 5, 1889.

Application filed March 15, 1888. Serial No. 267,249. (No model.)

To all whom it may concern:

Be it known that I, FERNANDO WHITE, a resident of Pittsburg, in the county of Allegheny and State of Pennsylvania, have invented a new and useful Improvement in Gas-Burners; and I do hereby declare the following to be a full, clear, and exact description thereof.

My invention relates to gas-burners, and more especially to a burner for illuminating purposes.

In burning gas for illumination it is essential in obtaining the greatest luminosity that the gas should be as highly heated as possible before it reaches the point of combustion. To obtain this result is the object of my invention, as well as to provide a burner which can be economically constructed.

To these ends my invention consists in certain combinations of parts, more fully herein-after set forth.

To enable others skilled in the art to make and use my invention, I will describe the same more fully, referring to the accompanying drawings, in which—

Figure 1 is a central vertical section of my improved burner, and Fig. 2 is a side view of the burner.

In constructing my improved burner, a body, *a*, which is preferably bell-shaped, has extending up through a threaded opening, *c*, at its smaller end, a pipe, *d*, which has one or more outlet-openings, *e*, for the escape of the gas. The pipe *d* serves as the supply-pipe of the burner, and, though it may be plugged at its upper end, I prefer to form threads *d'* thereon and extend the same above the edge of the body *a*, so that it can engage a threaded opening, *f*, in a cover-plate, *g*, which plate has the outer edges of its under face ground off, so that the plate will fit tightly against the top edge, *a'*, of the body *a* when the plate is screwed down on the threaded end *d'* of the pipe *d*. By this construction the supply-pipe *d* also serves to hold the cover-plate *g* securely against its seat *a'* on the body *a* without the use of any bolts or screws.

Where the service-pipe is to be attached to the bottom of the pipe *d*, the threaded opening *f* is closed at its upper end by the screw-

plug *h*; but when it is desired to hang the burner from the service-pipe the lower end of the pipe *d* is closed by a cap and the service-pipe screwed into the threaded opening *f*, instead of the plug *h*. Thus by the construction 55 of the burner it may be placed in either position. To regulate the flow of the gas from the supply-pipe *d* into the chamber *i*, formed by the body *a* and the cover-plate *g*, a sleeve, *j*, incloses the pipe *d* at its outlets *e* and extends up to the cover-plate *g*, so that an outlet for the gas into the chamber *i* is formed 60 between the cover-plate and the top of the sleeve *j*, which outlet may be varied more or less in size by moving the sleeve to and from 65 the cover-plate. The preferable method of attaching this sleeve to the pipe *d* so that it can be moved up and down is to form a threaded flange, *j'*, on the lower end of the sleeve, which flange engages threads formed 70 on the pipe *d*, which permits the necessary amount of movement for the adjustment of the position of the sleeve by screwing the sleeve up or down.

To permit the escape of the gas from the 75 chamber *i*, so that it can be burned, a series of downwardly-projecting holes, *l*, are formed in the body *a* a short distance below its edge *a'*, the effect of the downward inclination of the holes being to throw the flame outward 80 from the body *a*, so that a perfect combustion is obtained, as the flame does not lick the sides of the body and prevent the access of air to the inner side of the flame. In order to prevent the flame from curling over the top 85 of the cover-plate *g* and insure that it will have a vertical direction, an upwardly-extending flange, *m*, is preferably formed on the top of the cover-plate *g* at its outer periphery, the flange having a slight outward inclination. 90

The operation of the burner is as follows: The gas coming in the pipe *d* either from the top or bottom passes through the outlets *e*, and is deflected upward by the walls of the sleeve *j* until it strikes against the cover-plate 95 *g*, and then shoots laterally out between the cover-plate and the top of the sleeve *j*, licking the under surface of the cover-plate as it moves toward its outer periphery, finally passing down the wall of the body *a* until it escapes 100

from the holes *l*, and then, mixing with the air, burns. After the gas has burned a short time the cover-plate *g* becomes heated by the hot gases and air which are above it, and thus 5 the unburned gas as it shoots along the under surface of this cover-plate is quite highly heated by the time it reaches the outer periphery of the plate, and is still further heated by its contact with the walls of the body *a* before it reaches the holes *l*, issuing from the latter at the proper temperature to secure perfect combustion for illuminating purposes. As the pressure of the gas forces the latter out of the holes *l*, the inclination of the holes 10 throws the flame away from the body *a*, so that air can have access to the inner side of the flame and prevent smoking. When the pressure on the service-pipe is high, the sleeve *j* is screwed up until a smaller space is left between the top of the sleeve and the cover-plate 15 *g*, and thus a smaller amount of gas will pass into the chamber *i*. If the pressure is low, the sleeve *j* is screwed down, so as to make the outlet into the chamber the maximum.

20 25 My improved burner gives a white light of great illuminating power with a minimum expenditure of gas.

Having now described my invention, what I claim is—

1. In a gas-burner, the combination of the body *a*, the gas-supply pipe *d*, extending into the same, said pipe having outlets *e* therein and having its upper end threaded, the cover-plate *g*, screwing onto the end of said pipe and resting against the top of the body *a*, and 30 a cap or plug, *h*, closing the end of the pipe *d*, substantially as and for the purposes set forth.

2. In a gas-burner, the combination of the body *a*, having the outlets *l*, the pipe *d*, extending up through the body and having outlets *e* therein, the cover-plate *g*, screwing onto said pipe and resting on said body, and the regulating-sleeve *j*, screwing onto said pipe and having an enlarged portion inclosing said outlet *e* and extending up toward said cover-plate, 35 substantially as and for the purpose set forth.

In testimony whereof I, the said FERNANDO WHITE, have hereunto set my hand.

FERNANDO WHITE.
